OF BROOKLYN, NEW YORK

STRINGED MUSICAL INSTRUMENT

Application filed August 28, 1929. Serial No. 388,866.

The present invention relates broadly to stringed musical instruments and more especially to stringed musical instruments provided with sounding posts.

5 It is customary to provide a stringed musical instrument with a resonating body to substantially enclose a predetermined volume of air; and certain types of musical instruments, usually stringed instruments 10 adapted to be played by a bow, are provided with sounding posts which extend between the fronts and backs of the instruments. The sounding post is usually located adjacent the bridge of the instrument in such manner as to transmit vibrations from the sound board directly to the back of the instrument, and in this manner, increases the resonance and volume of the tones produced by the 15 strings. The sound post construction has 20 considerable to do with the quality and tone of the instrument and should be of light weight, or small mass, so as not to dampen the vibrations. Sound posts are usually made of light strong wood, and spruce is commonly employed for this purpose. Such 25 solid wood posts, however, seem to interfere with the air vibrations in the resonant body.

It is particularly desirable that the entire 30 volume of air within the body of the instrument shall be free to vibrate throughout the body of the instrument without being broken by intermediate parts. It has been found by experiment that a sound post constructed of light tubular material, being elastic and 35 at the same time rigid, substantially increases the quality and tone of the instrument. The tone is further greatly improved by providing the sound posts with a large number of transverse openings in such manner that the 40 air vibrations in the body of the instrument are not interrupted by the sound post itself, but may pass directly through the post without being reflected or diverted by the sides of the post. It has been further determined 45 that a very thin hardened steel tube perforated with a plurality of openings and provided on its ends with tightly fitted wooden plugs comprises an excellent construction for carrying out the purpose of the present 50 invention.

Experimentation has also shown that the quality and tone of the instrument may be further improved by providing a small tubular member adjacent the base of the instrument, which member is perforated with a 55 plurality of openings in such manner as to prevent the member from forming a tuned resonating cup. To this end, this improvement may be accomplished in instruments having a supporting peg, such as cellos and double basses, by providing a longitudinal opening in the supporting peg, which opening leads to the resonance chamber in the body of the instrument, and which opening is in communication with the outer air 60 through a plurality of lateral holes leading through the walls of the peg. These lateral holes prevent the chamber in the peg from forming a resonant pipe. The operation of this improved structure is not well understood, although the effect is very noticeable. It is probable that the opening in the base of the instrument relieves this portion of the 65 resonating chamber of the instrument from any deadening effect which may be produced on the waves of the body of the instrument because the base of the instrument is one of 70 the least resonating parts thereof.

In instruments of the violin or viola type the same improved result may be obtained by 75 providing a perforated tubular member comprising a tail piece button with a longitudinal opening which communicates with the resonating chamber of the instrument and is connected to the outer air by a plurality 80 of lateral openings, thereby preventing the chamber from forming a tuned resonating tube.

Referring now to the drawings, Fig. 1 illustrates a cross section through an instrument 85 of the cello or double bass type provided with the improved sound post and supporting peg carried by the bottom of the instrument.

Fig. 2 is an enlarged view of the preferred 90 form of improved sound post.

Fig. 3 illustrates a section through Fig. 2 on line 3-3.

Fig. 4 illustrates a section through the improved violin tail piece button and a por- 100

tion of the side wall of the base at the bottom end of the violin.

Referring now more especially to Figs. 1, 2, and 3, the instrument illustrated in Fig. 5 1 is an instrument of the cello or double bass type provided with a neck portion 1, a sound board 2, a back 4, a bridge 5, strings 6, tail piece 7, and supporting peg 8. The sound post 9 of the improved type extends between 10 the sound board 2 and the back 4. The supporting peg 8 is provided with a longitudinal 10 which leads into the resonating chamber 11 of the body of the instrument. A plurality of lateral openings 12 are provided in 15 the supporting peg 8 and these lateral openings lead to the longitudinal opening 10 in such manner as to prevent the longitudinal opening 10 from becoming a tuned resonant column of air.

20 Referring now more especially to Figs. 2 and 3, which illustrate a preferred form of the sound post 9, this sound post, in this preferred form, is constructed of a rigid tube 14 provided with a large number of side wall 25 openings 15, and is plugged at the ends with wooden plugs 16 which fit tightly into the tube and, if desired, may be cemented in place. A hardened steel thin walled tube has been found by experiment to comprise the preferred material from which to construct the sound post. It is desirable that the side wall of the tube shall be extremely thin, much thinner than illustrated in Figures 2 and 3, wherein thickness of the side wall is shown 30 merely for the purpose of illustration of other features. It is particularly desirable that the openings 15 shall be numerous and preferably the openings on opposite sides of the tube are diametrically opposite each other, so that air 35 vibrations may pass through the tube without substantial interruption. The end plugs 16 are provided to enable the instrument maker to fit the ends of the sound post properly into the instrument and also to prevent 40 the ends of the tube from cutting either the sound board or the back of the instrument.

45 Fig. 4 illustrates the tail piece button of a violin or viola, and comprises a button member 17 provided with a longitudinal opening 50 18 from which leads a plurality of lateral openings 19, also preferably inclined openings 20 extend diagonally from the outer portion of the button into that part of the button which passes through the end wall 21 55 of the instrument, so that there is no part of the longitudinal chamber 18 which is not in communication with the outer air. The same kind of oblique or inclined openings may be provided in the supporting peg 8 60 used in cellos and basses, to reach the longitudinal opening in the part of the tube extending through the bottom wall of the instrument.

In the old well known construction of 65 string instruments, the solid sound post and

the closed ends of the resonating body appear to cause slight distortions in the air waves or vibrations within the resonating chamber in the instrument body, so that an artist is compelled to use great skill and effort to bring out the best in the instrument.

70 These new improvements prevent and obviate the air wave distortions so that the result is a clear brilliant sparkling tone which flows freely from the instrument which is instantly responsive to the mastery of the skilled artist.

What I claim is:—

1. A string musical instrument provided with a body comprising a resonating chamber and a perforated tubular member having a large number of holes in the side wall thereof from one end of the member to the other and communicating with said resonating chamber.

80 2. A string musical instrument having a body comprising a resonating chamber and a tubular member provided with a plurality of diametrically opposed lateral openings, said tubular member being operatively connected with said resonating chamber.

90 3. A sound post for stringed instruments comprising a tubular body provided with a plurality of perforations from one end to the other and extending through the side walls 95 of said tubular body.

100 4. A sound post for stringed musical instruments comprising a metallic tubular member having a plurality of opposed lateral openings through the side wall for substantially the full length of said member and with a plug member in each end of said tubular member.

105 5. A sound post for stringed musical instruments comprising a hardened steel thin walled tube provided with a plurality of lateral openings and with non-metallic plugs in the ends of said tube.

110 6. A sound post for stringed musical instruments comprising a tubular body portion provided with a large number of diametrically opposed transverse openings through the side wall of said tubular body portion.

115 7. A sound post for stringed musical instruments comprising a hardened steel cylindrical tube with a thin side wall having a plurality of diametrically disposed openings in said side wall, and wooden plugs in the ends of said tube to form supports adapted to set against the front and back of a musical instrument.

120 8. In a string musical instrument having a body forming a resonating chamber, the combination of a hollow sound post extending across said resonating chamber and provided with a plurality of transverse openings through which sound waves in said chamber may freely pass, said openings being so spaced lengthwise of said post that the en- 125

tire hollow part thereof is so perforated as to prevent interception and distortion of said sound waves.

9. A sound post for musical instruments comprising a tubular body having a large number of lateral openings through the tubular portion of said body, and plugs inserted in the ends of said tubular body.
